UNITED STATES PATENT OFFICE.

THOMAS B. JEFFERY, OF CHICAGO, ILLINOIS.

BICYCLE-BACKBONE.

SPECIFICATION forming part of Letters Patent No. 359,608, dated March 22, 1887.

Application filed August 23, 1886. Serial No. 211,603. (No model.)

To all whom it may concern:

Be it known that I, THOMAS B. JEFFERY, a citizen of the United States, residing at Chicago, in the county of Cook and State of Illinois, have invented certain new and useful Improvements in Bicycle-Backbones, which are fully described and set forth in the following specification, reference being had to the accompanying drawings, forming a part thereof.

Figure 1 is a side elevation of the neck-piece, showing the position of the seat and of the drive-wheel in dotted line. Fig. 2 is a rear elevation of the same. Fig. 3 is a plan of the same. Fig. 4 is a rear elevation of the rear portion of the backbone, including the fork, the forward part being broken away. Fig. 5 is a side elevation of the same, one branch of the fork being broken away. Fig. 6 is a rear elevation of the rear fork at one stage in the process of its manufacture. Fig. 7 is a section through b b , Fig. 1. Fig. 8 is a section of the backbone slightly modified from the form shown at Fig. 7, but taken at substantially the same point as Fig. 7.

A is the head-piece, which is in the usual form, except that the rear portion, A', onto which the backbone is joined—usually by brazing—is made hollow, and to compensate for the diminution of strength is extended rearwardly on the lower side in the tongue A¹⁰, giving it greater surface for brazing to the backbone, and affording strength at the point where the strain is most severe. When this part is made solid it is practically absolutely rigid, and its inelasticity causes the strain to be concentrated upon the tubular backbone at the end of this solid part, so that the backbone is especially liable to break at that point when subjected to severe strain. When, however, this part is made tubular, it is absolutely rigid only where it joins the stem A², and by tapering it out at the rear in the tongue A¹⁰ and securing the tubular backbone outside of it the stiffness of the structure is gradually increased toward the stem, and the strain is thereby distributed, instead of being concentrated at one point.

B is the backbone. C is the saddle. D is the drive-wheel.

In order that the distance from the saddle to the axle (and hence to the pedals) may be shortened without diminishing the diameter of the wheel or weakening the parts materially,

I compress vertically that portion of the backbone between the saddle and the wheel—viz., the part in the rear of the dotted line b b . The form thereby given to the cross-section may be elliptical, as in Fig. 7, or preferably, on some accounts, approximately D-shaped, with the more convex curve uppermost. In either of the flattened forms the vertical elasticity is somewhat greater than when strictly circular. This vertical compression may be continued to the extreme forward end, and in that case the rear portion, A', of the neck-piece is necessarily similarly compressed to receive the backbone and joined thereto, as shown.

B' B' is the rear fork. It has heretofore been customary to make the rear fork in a separate piece and join it by brazing or riveting onto the backbone. I avoid the expense of making this junction and increase the strength of the structure by making the backbone and fork of one piece of tubular metal, the tube being curved over the drive-wheel, as usual. It is by suitable devices compressed longitudinally and expanded transversely at a point, b', just above the fork. The longitudinal compression furnishes metal for the transverse expansion, and I prefer to compress longitudinally enough to increase the thickness at the expanded part beyond what it was before expansion, so that the strength and stiffness at that part shall be proportionate to the strain to which it is subjected. The expanded portion is medially cut away or rifted a little distance below or rearward from the point b', and the lateral portions B' B' are somewhat farther spread apart, and thus form the fork. Each lateral portion B' is thus left concavo-convex in cross-section, and they are afterward drawn tapering, and at the rear lower extremities are flattened to form the eyes b² b², which receive the axle of the rear wheel.

I claim—

1. A bicycle-backbone and rear fork made in one piece, the backbone being tubular and medially rifted in the plane of the curvature to form the fork, and thickened at the vicinity of the rift, substantially as set forth.

2. A bicycle-backbone and rear fork made of a single piece of tubing expanded at b' and rifted beyond such expanded portion, and the two branches laterally separated to form the rear fork, substantially as set forth.

3. A bicycle-backbone and rear fork made of a single piece of tubing expanded transversely and thickened at b' , and rifted beyond that point to form the fork to admit the rear wheel, substantially as set forth.

4. In combination, substantially as set forth, the neck-piece A, having the rearwardly-extended part A', made tubular and prolonged at the lower side in the tongue A¹⁰, and the tubular backbone lapping said tubular part A' and tongue A¹⁰, and secured thereto.

5. A bicycle-backbone made tubular, having its vertical diameter less than its horizontal diameter at the upper forward part, substantially as set forth.

In testimony whereof I have hereunto set my hand, in the presence of two witnesses, this 17th day of August, A. D. 1886.

THOS. B. JEFFERY.

Witnesses:

CHAS. S. NEEROS,
W. T. DAWSON.
